UNITED STATES PATENT OFFICE.

RICHARD E. PICKTHALL, OF SOMERVILLE, MASSACHUSETTS, ASSIGNOR TO
RHODES LOCKWOOD, OF ARLINGTON, MASSACHUSETTS.

DESIGN FOR A NURSING-NIPPLE.

SPECIFICATION forming part of Design No. 31,677, dated October 17, 1899.

Application filed September 19, 1899. Serial No. 731,030. Term of patent 14 years.

To all whom it may concern:

Be it known that I, RICHARD E. PICKTHALL, of Somerville, Middlesex county, State of Massachusetts, have invented and produced a new and original Design for Nursing-Nipples, of which the following is a specification, reference being had to the accompanying drawings, forming part hereof, in which—

Figure 1 is a perspective view of my nipple, Fig. 2 is a plan view, and Fig. 3 a section on plane 3 3 of Fig. 1.

The design is for a nipple for nursing-bottles; and it consists in having a spherical head

or mouth set upon the small end of a truncated cone, as is best shown in Fig. 1 of the 15 drawings.

In the drawings the lower edge of the truncated cone A is furnished with a rim or bead a, and the spherical head is marked B.

I claim—

The design for a nursing-nipple as herein shown and described.

RICHARD E. PICKTHALL.
